United States Patent Office

Des. 234,166
Patented Jan. 21, 1975

234,166

SIGN

Leslie M. Silverman, 2 Kansas St.,
San Francisco, Calif. 94103

Filed Oct. 12, 1972, Ser. No. 297,048

Term of patent 14 years

Int. Cl. D20—03

U.S. Cl. D96—3

FIG. 1.

FIG. 2.

FIG. 3.

FIG. 4.

FIG. 5.

FIG. 7.

FIG. 8.

FIG. 6.

FIG. 1 is a front perspective view of a sign embodying my new design;

FIG. 2 is a fragmentary rear perspective view thereof on an enlarged scale;

FIG. 3 is a side elevational view thereof on an enlarged scale;

FIG. 4 is a front perspective view of another embodiment of my new design;

FIG. 5 is a side elevational view thereof on an enlarged scale;

FIG. 6 is a front perspective view of another embodiment of my new design;

FIG. 7 is a fragmentary top plan view thereof on an enlarged scale; and

FIG. 8 is a side elevational view thereof on an enlarged scale.

The sign is fragmentarily shown in FIGS. 2 and 7 for convenience of illustration. The wall shown in broken lines in FIG. 5 is for illustrative purposes only.

I claim:

The ornamental design for a sign, substantially as shown and described.
